COMMUNICATION SYSTEM

Walter S. Lemmon, New York, N. Y., assignor to
 International Business Machines Corporation,
 New York, N. Y., a corporation of New York

Application May 18, 1935, Serial No. 22,200

3 Claims. (Cl. 178—23)

This invention relates to communication systems and more particularly to printing telegraph systems and is suitably adaptable to both radio and wire network transmission.

- 5 The present invention will be explained in conjunction with a single impulse synchronous transmission system, in which the different characters to be transmitted and received are represented by single impulse signals which are definitely allocated during particular timed intervals. Inasmuch as the wave shapes of the signals may be all the same length and amplitude with respect to time, they can be similarly dealt with in transmission.
- 10 15 This invention consists of a method and means for the transmission and reception of printing telegraph signals, the system being characterized by the transformation of the wave shape of the signal during the progress of its transmission or reception or both.

An object of this invention is to provide abbreviating means for controlling the time duration of the character pulse independently of the time duration of the impulse impressed on the input of the receiving system.

Another object of the present invention is to provide means for accomplishing the abbreviation of the signal impulses mechanically.

Various other objects and advantages of the invention will be obvious from the following particular description of one form of mechanism embodying the invention or from an inspection of the accompanying drawing; and the invention also constitutes certain new and useful features of construction and combination of parts hereinafter set forth and claimed.

In the drawing:

- Fig. 1 shows a partial sectional view of the preferred form of signal source or transmitter.
- 40 Fig. 2 shows diagrammatically the circuits which may be used to embody the present invention.

It has been found that in synchronous systems of the type to be described, namely, the single impulse system, the margins of operation at higher rates of transmission become quite limited. For such rates of transmission, it is necessary to maintain exact synchronism between the transmitting and receiving distributors, and in addition thereto, to transmit and receive the character signals by extremely short impulses, so as to be positioned or allocated properly on the distributor segments. However, it is well understood by those acquainted in the art, that transmission of signals either by radio or line networks under

such critical conditions set forth numerous disadvantages, and prevent the higher rates of transmission of character signals without utilizing complicated and elaborate correcting systems, which for commercial application and operation would be impractical.

It has been suggested to utilize a longer impulse for transmission purposes, and which is necessary for radio transmission due to distortion and mutilation of the signal wave shapes, and upon its reception at the receiver, to suppress or abbreviate the signal so as to impress but a part of it upon the respective distributor segments.

A system of this type is disclosed in a copending application Ser. No. 730,906, filed June 16, 1934, the principle of which, applied to the above mentioned system rendering faster possible rates of transmission than heretofore. The system just mentioned in the said application is based on an electrical abbreviating system utilizing thermionic devices adapted to trigger controlling electrostatic devices.

The present invention contemplates a similar treatment of the signal wave shapes, however, in contradistinction to the electrical abbreviator provides for a simple and efficient mechanical abbreviator, the disclosure of which will be set forth presently.

It has been mentioned that the particular embodiment of this invention is in conjunction with a particular type of printing telegraph system, however, its application is not limited to the preferred form of illustration, for it will be understood, as the description progresses, that the invention is obviously applicable to other types of selecting or control systems in which signal overlap on distributor or commutator segments or the like is likely to occur.

It was mentioned hereinbefore that the particular type of communication system explained in conjunction with the present invention is a printing telegraph system operable by a line or radio network and involves the shifting of the character impulse along the axis of a timed scale, the position of the impulse thereon determining the character to be selected, and is of the type disclosed in U. S. Patent No. 1,927,077, dated September 19, 1933.

Referring now to Fig. 1, a printing telegraph translating unit is shown, one well known form of which may be the Electromatic typewriter disclosed in the copending application Serial No. 676,654, filed June 20, 1933 and hence requires only the following brief description.

In the embodiment illustrated in the drawing,

well known means are provided for actuating the type bars (not shown) by power operated devices comprising a power driven roller 10.

5 A cam 11 is pivoted on one arm of a bell crank lever 12 pivoted in the frame, the other arm of which is operatively connected with one arm of a bell crank lever 13 by means of link 14. The other arm of lever 13 is connected to the type bars (not shown) in a well known manner and 10 fully disclosed in the aforesaid application.

10 The lever 12 is actuated by the cam 11 when the latter engages the driven roller 10 to be operated thereby. The engagement of the cam 11 with the power roller is controlled by means of 15 the key lever 17 in a manner which will now be described.

The cam 11 is resiliently engaged by a spring-pressed arm 20 which tends to turn it into engagement with the power driven roller or stop 20 21 on a lever 22 pivoted on the bell crank 12 and normally arranged in the path of a lug on the cam. When the lever 22 swings to move its stop 25 out of the path of the lug, the arm 20 swings the cam into engagement with the power roller 25 to be actuated thereby to swing the bell crank 12 to actuate its connected mechanism.

The lever 22 has an arm 24 which is provided with an offset projection 25 at its end which projects laterally through an opening in the bell 30 crank 12 and engages the bifurcated lower end 26 of an arm 27 of a key lever 17 pivoted on the common rod 28.

It is obvious then that depression of a key 35 lever 17 releases the revolvably mounted cam 11 to engage and be actuated by power roller 10 in turn operating bell crank 12 and its attached links to cause the associated mechanism, such as the key bars and other operating mechanisms, to be operated.

40 Attached to the key lever 17 is a connecting link 19 extending to a solenoid 18 disposed beneath the keyboard, so that upon energization of the said solenoid the connected key lever is depressed to operate the connected mechanism in the same manner as just explained.

45 In addition to actuating the several type bars and connected mechanisms, the revolvably mounted cams are adapted to make and break circuits which may be employed in the transmitting units, the purpose of which will be understood as the 50 description progresses. Upon release of the cam 11 the ensuing operation thereof causes the contact spring blade 30 by virtue of its attached cam follower roller 31 adapted to engage the cam during its partial revolution, to be urged away from the power roller 10 to open the contacts 32 and close the contacts 33. Since the cam turns exactly one half of a revolution before being arrested, the spring blade 30 returns to its normal 60 position as shown in the drawing by virtue of its own resiliency, thereby restoring the contacts to their normal position, that is, contacts 32 closed and contacts 33 open.

65 It will be understood that the usual number of key bars and power devices with their associated mechanisms are provided, but only one of them is shown for the sake of clearness.

70 Referring now to Fig. 2, A represents a printing telegraph unit which may be of the type described or any well known type having a series of character pivoted key bars 17 and adapted to initiate a character impulse when one of the character keys is depressed.

75 The transmitting contacts may be positioned as explained hereinbefore so as to open one set of

contacts and close another by the operating cams 11 or the contacts may be positioned directly in contact with the keyboard 17 and operated thereby, as shown in the figure.

80 A separate contact 32a is associated with each individual key bar 17 and connected to segments 35 of the distributor 36, a portion of the development of which is shown, and further disclosure thereof is deemed unnecessary since their use is well known in the art. Rotary arm 37 driven by 10 any suitable means, such as a motor, is adapted to engage the segments in rather rapid succession to cause the transmission of the character impulses. One method of setting up the character signals is by the use of condensers and as 15 shown an individual condenser 38 is associated with each key bar 17, the said condensers associated with the key bars are connected by a common conductor 39 to the negative side of battery 40. It is to be noted that all the contacts 32a, 20 that is, the normally closed contacts, are associated with separate conducting segments 35 of the distributor 36.

25 Disposed beneath or associated with the key bars 17 and normally open are the contacts 33a 25 connected to one side of the condensers 38. These are provided so that when a character key is depressed the condenser 38 normally charged will be discharged by shorting the condenser through contact 33a to ground.

30 Supposing the key bar corresponding to character A is depressed to discharge its corresponding condenser, upon return of the key bar the contact 32a would be closed to connect the circuit from the negative side of battery 40 through condenser 38 and the closed contact 32a to its corresponding segment 35-1, so that when the rotary arm 37 with its conducting brush 42 engages contact 1, a circuit is completed through its other brush 43, solid and common conducting distributor ring 40 44, conductor 45 and the connected parallel circuit consisting of resistors 46 and the primary winding of transformer 47, to the positive terminal of battery 40. Therefore, it is seen that upon completion of this circuit just described, by 45 the rotating arm 37 engaging the segment 35-1 of the distributor the corresponding condenser conditioned upon depression of the A character key by being discharged is now charged through the parallel circuit arrangements 46 and 47 to energize the secondary winding of transformer 47 and its connected circuit which may be a wire or 50 radio transmission network, utilizing transmitting equipment well known in the art, and therefore deemed not necessary to describe in further 55 detail.

55 It was mentioned that the condensers 38 were assumed to be normally charged, therefore, in order to insure correct operation of the transmitting system upon starting, the normally closed 60 switch 49 included in the input circuit of the signal transmitter is opened, until the individual condensers, which may have been discharged, are charged by having all the distributor segments 35 engaged successively by the rotary arm 37 in 65 a manner just described, and in this manner prevent erroneous operation of the receiving system which will now be explained.

70 The broad principle of operation of single impulse systems of the type referred to, which is 70 obvious, depends upon the synchronous operation of the distributing or rotary units associated with the respective transmitting and receiving units. Such synchronizing units are old and well known to those skilled in the art, and therefore a de- 75

tailed description of this unit is not necessary. It is sufficient to mention that one type of synchronizing unit is such utilizing periodic synchronizing impulses, as, for example, a synchronizing impulse for each revolution of the transmitting rotary distributor, and usually are arranged so that if the rotary distributor at the receiver lags as compared to the rotation of the transmitting distributor, the receiving rotary brush, by virtue of such lagging, engages a contact segment to energize electro-responsive devices by the transmitted synchronizing impulse to cause the rotary arm at the receiver to be advanced to such an extent during its rotation so as to traverse the distributor segments in step with the transmitting distributor. If the receiving rotary arm is leading the transmitting arm, engagement of another contact segment causes the electro-responsive devices to retard the rotation of the rotary arm until synchronous operation is attained. For a complete description of a synchronizing unit of the type just mentioned, reference may be made to the copending application Serial No. 684,362, filed August 9, 1933 and which can be embodied in this application.

A receiving distributor 51 similar to the transmitting distributor 36 has disposed thereon the same number of segments 52 which are engaged in succession by brush 53 attached to rotary arm 54 driven by a suitable motor or device (not shown) so that the arms 51 and 37 are rotated synchronously.

The aperiodically timed character signals are received in the well known manner by a receiver, generally designated, which in turn is associated with a standard and well known type of amplifier 58 consisting of a plurality of thermionic tubes of which two are shown and designated 56 and 57 arranged in cascade and coupled by transformers in the usual manner.

The output of amplifier 58 is connected by one lead to the common conducting ring 59 of distributor 51 constantly engaged by brush 60 also attached to rotary arm 54. The individual segments 52—1, 2, 3, etc. are connected by individual conductors 61 to one terminal of solenoids 18, which as described hereinbefore are linked to a corresponding character key bar 17.

The other terminals are all connected to a common conductor 62 which forms a return circuit for the output of the said amplifier.

An auxiliary timing distributor 63 is employed having disposed thereon a plurality of conducting segments 64 corresponding in position and disposition to the segments 52, with the exception, however, that the segments 64 are shorter in length than the segments 52. The said segments 64 are all joined to a common conductor 65 which is connected to the cathode of tube 57. Segments 64 are adapted to be engaged in succession by a brush 66 attached to rotary arm 67, said arms 67 and 54 may be arranged on a common driven shaft so as to be operated in unison. Conducting brush 68 constantly engages the common solid segment 69 which in turn is connected to the one terminal of the transformer winding, the other end of which is connected to the grid of tube 57, completing the grid circuit whenever the brush 66 engages one of the segments 64.

The segments 64 are so arranged to be engaged by the brush 66 when the distributor brush 53 engages the central section of the segments 52. So that upon reception of a character pulse, corresponding to the character A, for example, the distributor arms 54 and 67 will be positioned as

described hereinbefore so that brush 53 engages segment 52—1 and brush 66 engages the segment 64—1 when brush 53 engages the central section of segment 52—1.

The character signal is received in the well known manner at the receiving station to energize the amplifier 58. However, it is seen that until the grid circuit of tube 57 is completed by the auxiliary distributor the solenoid 18 is not energized by the impulse.

It was mentioned that the segments 64 are shorter than segments 52 and, it is obvious, that the grid circuit of tube 57 is broken or opened by the auxiliary distributor 63 before the brush 53 is disengaged with the corresponding segment. Therefore, it is possible by controlling the timing operation of the control grid of tube 57, the signal pulse may be allocated on the receiving distributor segments 52 at any predetermined section thereof. In addition thereto, by virtue of the short segments 64, overlap is prevented on the distributor segments 52 due to the abbreviated pulse, and in this manner permit a slightly greater drift or synchronizing margin and tolerance.

In order to operate the described system at greater rates of speed an abbreviator method of the type disclosed is highly desirable because the operating margins are increased.

It is obvious that the solenoid 18 upon energization by the signal pulse functions to depress the correspondingly linked key bar 17 to release the revolubly mounted cam 11 to engage and be actuated by the power roller 10 in turn operating the associated bell crank 12 and its attached links and mechanisms to operate the type bar corresponding to the transmitted character pulse, in the example chosen, character A and recording the said character accordingly.

In such cases when the abbreviated pulses are not long enough to energize the solenoid 18 directly, a condenser 70 can be bridged across the solenoid 18 to prolong the pulse charge in accordance with the characteristics of the said circuit.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In a communication system, a sender and a receiver, each having a circuit control device, the operation of each of said devices being in timed relation with that of the other, a signal key at the sender, a transmission circuit, means whereby signal impulses corresponding to operations of said signal key are transmitted to said transmission circuit at instants of time governed by the operation of said circuit control device of the sender, said receiver having recording means governed by the circuit controlling device of the receiver, thermionic discharge means associated with said receiver operated by said impulses to be discharged to operate the said recording means, and a mechanical interrupter operated in synchronism with said circuit control device at the receiver to initiate and terminate the discharge of said thermionic means.

2. In a communication system, means to transmit character impulses including rotary means to initiate differentially timed impulses repre-

senting different characters, and means cooperat-
ing therewith to select the time to initiate the
differentially timed impulses corresponding to the
particular characters to be transmitted, recording
means, means to receive the said character im-
pulses including rotary means operating in syn-
chronism with the first mentioned rotary means
to govern the time of operation of the recording
means, thermionic discharge means associated
10 with the said receiving means operated by the
said impulses to be discharged to operate the
recording means, and a mechanical interrupter
operating in timed relation with the rotary means
at the receiver to initiate and terminate the dis-
15 charge of the said thermionic means.

3. In a communication system, in combination,
a sending rotary distributor including a series of
control segments, a series of printer actuating
members each associated with one of the control

segments and adapted to transmit printing im-
pulses, means to receive said impulses including a
receiving rotary distributor operating in substan-
tial synchronism with the sending distributor,
said distributor having disposed thereupon a series 5
of control segments, a series of recording operating
elements each associated with one of the last
mentioned control segments, the operation of
which is governed by the receiving distributor,
thermionic discharge means having grid and 10
plate circuits operated by the printing pulses im-
pressed on the grid circuit to be discharged to
operate the said recording elements included in
the plate circuit, and an additional control dis-
tributor disposed in the grid circuit to initiate 15
and terminate the discharge of the thermionic
means.

WALTER S. LEMMON.
